UNITED STATES PATENT OFFICE.

CARL JOHANNES RUTHS, OF DJURSHOLM, SWEDEN.

STEAM-SUPERHEATER ARRANGEMENT IN PLANTS PROVIDED WITH STEAM-ACCUMULATORS.

1,294,714.

Specification of Letters Patent.

Patented Feb. 18, 1919.

Application filed January 11, 1917. Serial No. 141,766.

To all whom it may concern:

Be it known that I, CARL JOHANNES RUTHS, subject of the King of Sweden, residing at Djursholm, in the Kingdom of Sweden, have invented certain new and useful Improvements in Steam-Superheater Arrangements in Plants Provided with Steam-Accumulators, of which the following is a specification.

10 In steam accumulators containing water the steam supplied from the accumulator is more or less wet. In many cases this is a considerable disadvantage, and it is therefore often desirable to more or less superheat the steam. The present invention relates to an arrangement to that effect and consists in providing the steam accumulator with a special superheater, or a special superheating device.

20 The superheater of the steam accumulator may, of course, be constructed as an ordinary superheater. It is, however, preferably so designed, as to store in the accumulator part of the heat contained in the live steam.

25 The superheater then imparts this heat to the steam delivered from the accumulator.

The above mentioned apparatus preferably consists of a receptacle filled with solid material, as iron langrage or stones. The 30 superheated charging steam flowing into the accumulator will heat the said material to a relatively high temperature. When the accumulator is discharged the steam flows from the accumulator through the said heat storing device, whereby the steam is superheated or dried. Even in case the steam accumulator does not contain water, but is constructed for instance as a gasholder, the storing of heat in a receptacle filled with a 35 heat storing material may be advantageous. The steam supplied to the accumulator may be assumed to be delivered either from a steam boiler, or from a steam engine after having done its work therein. The steam 40 obtained from the accumulator may be used for many different purposes.

In the drawings which show my steam superheater arrangement diagrammatically, Figure 1 illustrates one embodiment there- 50 of; Fig. 2 shows a modification; Fig. 3 illustrates another embodiment of my invention and Fig. 4 another modification. Like parts are designated by the same reference characters in all the figures of the drawing.

In Fig. 1 the superheated steam is sup-

plied from a steam boiler (not shown) through the pipe l^1 and enters the receptacle a , which is filled with a heat storing material S consisting of iron langrage, stones or the like. In passing through a , the superheated steam yields part of its heat of superheat and in certain cases, *i. e.* when the accumulator is cold as when steam is first introduced even part of its latent heat. After having thus yielded heat, the steam escapes 60 through the automatic stop valve r^1 and the pipe l^2 to the steam accumulator b which is filled for the greater part with hot water v . The steam flows into this water through a large number of holes m in the pipe l^2 and 70 is condensed. During the discharging period, the steam flows from the accumulator b through the pipe l^3 and the automatic stop valve r^2 at the end of said pipe into the receptacle a , and in passing through the heat 75 storing material S , it receives part of the heat stored therein. The steam finally passes in a superheated or dried condition through the pipe l^4 to the place of consumption.

In Fig. 2, the heat storing device is in- 80 closed in the steam accumulator b , the heat storing material S being carried on a grating g , or the like. The steam, entering through the pipe l^4 , passes through S and is condensed by coming into contact with 85 water jets from the holes m in a pipe l^5 . As shown, the circulation is effected by a centrifugal pump p which draws the water from the lower part of the accumulator b through the pipe l^6 and presses it back through the 90 said pipe l^5 , the water being discharged therefrom through the said holes m for condensing the steam. During the discharging period, the steam leaves the accumulator b through the heat storing 95 device S , and it is thereby dried or superheated before it passes out through l^4 to the place of consumption. This arrangement offers a minimum of resistance to the charging steam.

In Fig. 3 the steam enters the receptacle a through the valve v^1 and the pipes l^7 and l^8 passes through the heat storing device S delivering heat thereto, and then flows through the pipes l^9 and l^{10} to the upper accumulator b entering into the water of the same through the holes m in the pipe l^{10} and being condensed. The steam accumulator consists of two parts, *viz.* the upper accumulator b and the lower accumulator c . The latter is com- 100 105 110

pletely filled with hot water whereas *b* is only partly filled the upper portion forming a steam chamber. The water level depends on the extent of the charging or discharging.

- 5 The circulation is such that water contained in the accumulator *b* flows into *c* through the pipe *l*¹¹ and is pumped back into *b* by the centrifugal pump *p* through the pipe *l*¹². During the discharging period, the steam in
- 10 leaving the accumulator *b* through the pipe *l*¹³, the valve *v*³, the water separator *d* and the pipe *l*⁹ passes through the receptacle *a*, wherein the steam is superheated by the heat storing material *S* before it flows farther on
- 15 through the valve *v*² and the pipe *l*¹⁴ to the place of consumption.

In Fig. 4 the superheated steam flows through the pipe *l*¹⁵ into the receptacle *a*, passes through the heat storing material *S* and enters by the pipe *l*¹⁶ into the upper accumulator *b*. On coming into contact with the water jets from the holes *m*, the steam is condensed. The condensed steam is carried together with the flowing water in a united stream through the cylindrical distributor *h* into the water of the accumulator *b*. As in Fig. 3 the accumulator consists of an upper part *b* and a lower part *c*. The circulation is such that water contained in the upper accumulator *b* flows through the pipe *l*¹⁷ into *c* and through the latter on a way determined by deflecting plates *P* to the centrifugal pump *p* which draws the water through *l*¹⁸ to the upper accumulator *b*,

During the discharging period, the steam escapes through *l*¹⁶ receptacle *a* and the pipe *l*¹⁵ in a superheated condition to the place of consumption.

The pipe *l*⁹ shown in Fig. 4 is provided for the purpose of establishing communication between the steam space in *b* and *c*, to compensate the pressures in *b* and *c*.

I claim as my invention:

1. The combination with a steam accumulator for superheated steam, of a heat storage device, steam conduits connecting the same, and means in said conduits for causing the steam to pass through the said heat storage device both on its way to and from the said accumulator. 50
2. An arrangement as specified in claim 1, in which the heat storage device comprises a receptacle containing heat storing material, preferably in a solid state. 55
3. The method of utilizing the heat of the superheat of superheated steam which consists in passing the superheated steam through a device adapted to absorb and store part of the heat of the superheat, then passing the steam on to a steam accumulator and afterward passing the steam from the said accumulator back through the said device. 60

In testimony whereof I affix my signature in presence of two witnesses.

CARL JOHANNES RUTHS.
